UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF BROADWAY, WESTMINSTER, ENGLAND.

RECOIL AND RUN-OUT APPARATUS FOR ORDNANCE.

Application filed July 2, 1927, Serial No. 203,135, and in Great Britain September 10, 1926.

This invention relates to ordnance recoil and run-out apparatus employing a pneumatic recuperator the interior of which does not communicate with the interior of the 5 recoil or brake cylinder, that is to say there is no transfer of liquid from the recoil or brake cylinder to the recuperator cylinder during the recoil of the gun. The invention is particularly intended for use with a 10 short gun barrel having a long recoil in relation to the length of the barrel and the chief object is to reduce as far as possible the over-all length of the recoil and run-out apparatus so that it will not materially exceed the length of the said short barrel.

According to the present invention the air in the recuperator cylinder is compressed by a piston during the recoil of the gun and the 20 rod of this piston is made of large diameter and hollow to form a reservoir of the required volume to store the compressed air, the air from the recuperator cylinder passing to the interior of the hollow piston rod during the recoil of the gun and returning 25 to the recuperator cylinder at the end of the recoil so as to act upon the piston and effect the run-out of the gun. A spring-controlled valve may be provided between the recuperator cylinder and the interior of the hollow 30 piston rod to permit free flow of air into the latter during recoil and this valve is so formed as to permit the air to return relatively slowly from the interior of the hollow piston rod to the recuperator cylinder so as 35 to prevent too quick a run-out movement of the gun.

The recuperator piston carries a gland, and in order to prevent leakage of air past this gland it is maintained tight by liquid 40 under pressure derived from an intensifying cylinder formed in the rear end of the piston rod close to the piston so that only a short conduit need be provided for the passage of the liquid from this intensifying cylinder to the gland under the influence of a 45 differential piston the larger face of which is in communication with the air in the recuperator cylinder.

The recuperator cylinder is preferably 50 formed in a forging or casting (herein termed the recuperator body) which is also formed with the recoil or brake cylinder, and this recuperator body may be provided

with an upwardly extending piece constituting a thrust member against which the 55 rear surface of the breech ring bears. The latter is secured to the said upwardly extending piece and the front part of the barrel may be provided with a ring or band resting on the body between upwardly extending 60 lugs and a forward portion of the body arranged at a higher level than the main part, and the front part of the barrel is prevented from lifting and moving sideways by pins which pass through the upwardly extending lugs on the body and through the ring or band on the barrel and which fit in holes in the said forward portion of the body. The said upwardly extending piece replaces the usual lug on the 70 breech ring.

The said higher level forward portion of the body may be formed with inter-communicating liquid replenishing cylinders which are arranged side by side and one of 75 which communicates with the rear end of the recoil or brake cylinder. This portion may also be formed with an intensifying cylinder arranged alongside one of the replenishing cylinders, this intensifying cylinder 80 having a differential piston supplying liquid to a gland, through which the recuperator piston rod passes, at a higher pressure than the air in the recuperator cylinder.

In order that the said invention may be 85 clearly understood and readily carried into effect, the same will now be described more fully with reference to the accompanying drawings, in which:—

Figure 1 is a sectional side elevation of a gun provided with recoil and run-out apparatus in accordance with this invention.

Figure 2 is a front view of Figure 1 with the parts at the front end of the recuperator 95 body removed,

Figure 3 is a section taken approximately on the line 3, 3 of Figure 1.

Figure 4 is a local section taken approximately on the line 4, 4 of Figure 1, and 100

Figure 5 is a section taken approximately on the line 5, 5 of Figure 1 and viewed from the front of the latter figure.

A is the gun barrel, A¹ is the breech ring thereof, B is the gun cradle, C is the recuperator body, D is the recuperator cylinder 105

formed in this body, D¹ is the recuperator piston, D² is the hollow recuperator piston rod, D³ is the valve controlling the passage of the compressed air to and from the interior of the hollow piston rod, D⁴ is the gland on the piston D¹, D⁵ is the intensifying cylinder for the gland D⁴, D⁶ is the differential area piston working in the cylinder D⁵, E is the recoil or brake cylinder, E¹ is the piston working in the cylinder E and E² is the rod of the piston E¹.

In the example shewn the recuperator body C is in the form of a casting or forging of substantially rectangular cross-section with the recuperator cylinder D and the recoil or brake cylinder E formed therein alongside one another. This body is arranged to slide in the gun cradle B upon corner guides B¹, B²—carried by the gun cradle as shewn in Figure 2 and has an upwardly extending piece C¹ constituting a thrust member against which the rear surface of the breech ring A¹ bears. The said piece C¹ is secured by studs C² to the breech ring A¹ and the front part of the barrel A is provided with a ring or band A² which rests on the body C between upwardly extending lugs C³, C⁴ and a forward portion C⁵ of the body C which portion is arranged at a higher level than the main part of the body. The front part of the body is prevented from lifting and moving sideways by pins C⁶, C⁷ passing through the upwardly extending lugs C³, C⁴ on the barrel and through the ring or band A² on the barrel A, the said pins fitting in holes in the forward portion C⁵ of the body C and being held in place by split pins or other suitable means.

The front end of the recuperator piston rod D² and the front end of the recoil or brake piston rod E² are connected to the front cap B² of the gun cradle and the recoil cylinder is replenished with liquid from two inter-communicating cylinders C⁶, C⁷ which are formed in the forward portion C⁵ of the body C and which constitute replenishing receptacles. The outer cylinder C⁶ has a filling plug C^{8x} and the inner cylinder C⁷ communicates with the recoil or brake cylinder E by means of a pipe C^{9x} communicating with a passage C^{7xx} leading to the rear end of the said cylinder E. The said portion C⁵ is also formed with an intensifying cylinder C⁸ to receive a differential area piston C^{8x}. The front part of the cylinder C⁸ contains liquid and communicates by a short hole C^{8xx} with a gland D⁶ for the recuperator piston rod D², and the rear part of this cylinder communicates by another short hole C⁹ with the interior of the recuperator cylinder D. The front end of the recuperator piston rod D² is provided with a screw-down valve D^{2x} and with a plug D^{2xx} which is removed when it is required

to charge or recharge the recuperator cylinder with compressed air, the valve D^{2x} being at such times opened and being closed when the charging or re-charging operation is completed.

The recuperator piston rod D² is made of large diameter (nearly as large as the piston D¹) and is hollowed out through practically its full length so as to form a reservoir of large volume to store the compressed air. The valve D³ near the rear end of the rod D² is normally held on its seat by a spring D^{3x} and controls a passage D⁷ communicating by holes D^{7x} with the recuperator cylinder D in front of the piston D¹. The said valve opens under the influence of the increased air pressure generated in the cylinder D by the movement of this cylinder relatively to the piston D¹ on recoil of the gun, and consequently a portion of the air from the said cylinder enters the interior of the hollow piston rod D² through the holes D^{7x} and the passage D⁷. The said valve is formed with one or more small holes (not shewn) or is otherwise suitably formed to allow the compressed air to return relatively slowly from the interior of the hollow piston rod D² to assist in effecting the run-out of the gun but at the same time preventing too quick a run-out movement. The return of the air takes place by way of the passage D⁷ and the holes D^{7x} through which the air enters the interior of the hollow piston rod as aforesaid. The final portion of the run-out movement may be retarded by the usual retarding ram E³ which enters an axial recess E⁴ formed in the recoil or brake piston rod E². The differential area piston D⁶ is arranged in the intensifying cylinder D⁵ to the rear of the valve D³ and its front or larger face is acted upon by the compressed air from the recuperator cylinder D, the air having access to this face through the above-mentioned holes D^{7x}. The rear part of the cylinder is filled with liquid which communicates by holes D⁸ with the gland D⁴ carried by the recuperator piston D¹. The said liquid is thus forced into the gland at a higher pressure than the compressed air in the cylinder D. A charging plug D^{8x} is provided which, when removed, enables the intensifying cylinder D⁵ to be charged or replenished with liquid which passes into the latter cylinder through an axial passage D⁹ in the rod of the differential area piston D⁶ and through lateral holes D^{9x}. Access to the plug D^{8x} is obtained by removing a detachable cover D⁸ at the rear end of the cylinder D.

It will be seen from Figure 1 that as a result of the decrease in the length of the recoil and run-out apparatus due primarily to the provision of the hollow piston rod D² as a reservoir for storing the compressed air, the front part of the said apparatus

does not extend materially beyond the muzzle of the gun. The gun barrel is comparatively short and has a long recoil in relation to the length of the barrel as aforesaid.

5. What we claim and desire to secure by Letters Patent of the United States is:—

1. In ordnance recoil and run-out apparatus for ordnance, the combination with a pneumatic recuperator cylinder and a recoil or brake cylinder the interior of which does not communicate with the interior of said recuperator cylinder, of a reciprocating member which compresses the air in the recuperator cylinder during the recoil of the gun, a gland on said member, an intensifying cylinder formed in said member, and a differential piston the larger face of which is in communication with the air in the recuperator cylinder and the smaller face of which is in contact with liquid in said intensifying cylinder, which liquid is thereby forced through a conduit into said gland at a higher pressure than the pressure of the air in the recuperator cylinder. 70

10. 2. In ordnance recoil and run-out apparatus for ordnance, the combination with a pneumatic recuperator cylinder and a recoil or brake cylinder the interior of which does not communicate with the interior of said recuperator cylinder, of a piston working in said recoil or brake cylinder, a separate piston working in said recuperator cylinder so as to compress the air therein during the recoil of the gun, and a rod of the latter piston made of large diameter and hollow to form a reservoir of the required volume to store the compressed air, 75

15. the air from said recuperator cylinder passing to the interior of said hollow piston rod during the recoil of the gun and returning to said recuperator cylinder at the end of the recoil to act upon the second mentioned 80

20. piston and effect the run-out of the gun. 85

25. 3. In ordnance recoil and run-out apparatus for ordnance, the combination with a pneumatic recuperator cylinder and a recoil or brake cylinder the interior of which does not communicate with the interior of said recuperator cylinder, of a piston which compresses the air in said recuperator cylinder during the recoil of the gun, a rod of 90

30. said piston made of large diameter and hollow to form a reservoir of the required volume to store the compressed air, a valve 95

35. between the recuperator cylinder and the interior of the hollow piston rod to permit 100

40. free flow of air into the latter during the recoil of the gun, and means whereby, during the run-out movement of the gun, said valve permits the air to return slowly from the interior of the hollow piston rod to the recuperator cylinder. 105

45. 4. In ordnance recoil and run-out apparatus for ordnance, the combination with a pneumatic recuperator cylinder and a recoil or brake cylinder the interior of which does not communicate with the interior of 110

50. said recuperator cylinder, of a piston which compresses the air in said recuperator cylinder during the recoil of the gun, a rod of 115

55. said piston made of large diameter and hollow to form a reservoir of the required volume to store the compressed air, a spring- 120

60. controlled valve between the recuperator cylinder and the interior of the hollow piston rod to permit free flow of air into the latter during the recoil of the gun, and means whereby, during the run-out movement of the gun, said spring-controlled valve permits the air to return slowly from the interior of the hollow piston rod to the recuperator cylinder. 125

65. 5. In ordnance recoil and run-out apparatus for ordnance, the combination with a pneumatic recuperator cylinder and a recoil or brake cylinder, a body in which said cylinders are formed and an upwardly extending piece on said body constituting a thrust member against which the rear surface of the breech ring of the gun bears. 130

70. 6. In ordnance recoil and run-out apparatus for ordnance, the combination with a pneumatic recuperator cylinder and a recoil or brake cylinder the interior of which does not communicate with the interior of said recuperator cylinder, of a piston which compresses the air in said recuperator cylinder during the recoil of the gun, a rod of 90

75. said piston, a gland on said piston, an intensifying cylinder formed in said piston rod close to the piston, and a differential piston the larger face of which is in communication with the air in the recuperator cylinder and the smaller face of which is in contact with liquid in said intensifying cylinder, which liquid is thereby forced through a conduit into said gland at a higher pressure than the pressure of the air in the recuperator cylinder. 100

80. 7. In ordnance recoil and run-out apparatus for ordnance, the combination with a pneumatic recuperator cylinder and a recoil or brake cylinder, a body in which said cylinders are formed and an upwardly extending piece on said body constituting a thrust member against which the rear surface of the breech ring of the gun bears, and means for attaching the breech ring to said upwardly extending piece. 105

85. 8. In ordnance recoil and run-out apparatus for ordnance, the combination with a pneumatic recuperator cylinder and a recoil or brake cylinder, a body in which said cylinders are formed, an upwardly extending piece on said body constituting a thrust member against which the rear surface of the breech ring of the gun bears, a band on the gun barrel in front of the breech ring, the lower part of said band resting on said body, upwardly extending lugs on said body 110

90. 9. In ordnance recoil and run-out apparatus for ordnance, the combination with a pneumatic recuperator cylinder and a recoil or brake cylinder, a body in which said cylinders are formed, an upwardly extending piece on said body constituting a thrust member against which the rear surface of the breech ring of the gun bears, and means for attaching the breech ring to said upwardly extending piece. 115

95. 10. In ordnance recoil and run-out apparatus for ordnance, the combination with a pneumatic recuperator cylinder and a recoil or brake cylinder, a body in which said cylinders are formed, an upwardly extending piece on said body constituting a thrust member against which the rear surface of the breech ring of the gun bears, a band on the gun barrel in front of the breech ring, the lower part of said band resting on said body, upwardly extending lugs on said body 120

100. 11. In ordnance recoil and run-out apparatus for ordnance, the combination with a pneumatic recuperator cylinder and a recoil or brake cylinder, a body in which said cylinders are formed, an upwardly extending piece on said body constituting a thrust member against which the rear surface of the breech ring of the gun bears, and means for attaching the breech ring to said upwardly extending piece. 125

105. 12. In ordnance recoil and run-out apparatus for ordnance, the combination with a pneumatic recuperator cylinder and a recoil or brake cylinder, a body in which said cylinders are formed, an upwardly extending piece on said body constituting a thrust member against which the rear surface of the breech ring of the gun bears, a band on the gun barrel in front of the breech ring, the lower part of said band resting on said body, upwardly extending lugs on said body 130

65. 4. In ordnance recoil and run-out appara-

behind said band, and pins passing through said lugs and band and entering holes in said body in front of said band.

9. In ordnance recoil and run-out apparatus for ordnance, the combination with a pneumatic recuperator cylinder and a recoil or brake cylinder, a body in which said cylinders are formed, an upwardly extending piece on said body, constituting a thrust member against which the rear surface of the breech ring of the gun bears, a portion of said body at the front and arranged at a higher level than the main part of said body, and a replenishing cylinder formed in said portion and communicating with the rear end of the recoil or brake cylinder.

10. In ordnance recoil and run-out apparatus for ordnance, the combination with a pneumatic recuperator cylinder and a recoil or brake cylinder, a body in which said cylinders are formed, an upwardly extending piece on said body constituting a thrust member against which the rear surface of the breech ring of the gun bears, a portion of said body at the front end arranged at a higher level than the main part of said body, two intercommunicating replenishing cylinders formed in said portion side by side, and a conduit leading liquid from one of these two cylinders to the rear part of said recoil or brake cylinder.

11. In ordnance recoil and run-out apparatus for ordnance, the combination with a

pneumatic recuperator cylinder and a recoil or brake cylinder the interior of which does not communicate with the interior of said recuperator cylinder, a body in which said cylinders are formed, an upwardly extending piece on said body constituting a thrust member against which the rear surface of the breech ring of the gun bears, a stationary piston which compresses the air in said recuperator cylinder during the recoil of the gun, a rod of said piston, a portion of said body at the front end arranged at a higher level than the main part of said body, two intercommunicating replenishing cylinders formed in said portion side by side, a conduit leading liquid from one of these two cylinders to the rear part of said recoil or brake cylinder, a gland through which the front part of said recuperator piston rod passes, an intensifying cylinder formed in said higher body portion along side said replenishing cylinders, and a differential piston in said intensifying cylinder, the larger face of this differential piston being in communication with the air in the recuperator cylinder and the smaller face being in contact with liquid in said intensifying cylinder so that this liquid is forced into said gland at a higher pressure than the pressure of the air in the recuperator cylinder.

ARTHUR TREVOR DAWSON.
GEORGE THOMAS BUCKHAM.
